J. F. MADDEN

DOUBLE EYED GUIDE

Filed Aug. 24, 1921

Inventor

Jesse F. Madden

By E. E. Overholt

Attorney

UNITED STATES PATENT OFFICE.

JESSE F. MADDEN, OF BROOKLYN, NEW YORK.

DOUBLE-EYED GUIDE.

Application filed August 24, 1921. Serial No. 495,008.

To all whom it may concern:

Be it known that I, JESSE F. MADDEN, a citizen of the United States, residing at Brooklyn, in the county of Kings and State of New York, have invented certain new and useful Improvements in Double-Eyed Guides, of which the following is a specification.

My invention relates to guides for the 10 strands of silk, cotton, and other textile materials, handled by knitting, braiding, and other textile machines.

My object is to provide a device of this character which may be used in any place, 15 and with any holder, where a one-eyed guide can be used, thus dispensing with the frequent necessity of providing an extra guide, with the loss of time, and breakage of guides and threads, and other well known 20 inconveniences and annoyances arising from the use of extra guides.

The peripheral formation of my guide is substantially the same as that of the ordinary single-eyed guide, but it is provided 25 with two eyes preferably on diametrically opposite sides of the centre, with the two faces of the guide at the opposite ends of said eyes concaved, and with the eyes flared 30 at their open ends to merge into said concave surfaces.

The invention consists in the construction of the device as a whole, resulting from the form and relative arrangement of the several parts thereof, as hereinafter particularly described and claimed, reference being had to the accompanying drawings, in which:—

Fig. 1 is a horizontal section of my guide.
Fig. 2 is a side elevation thereof.

Fig. 3 is a side elevation with the relative position of the guide holder shown in dotted lines, and also with a diagrammatic representation in dotted lines of two strands or threads as they pass through the 45 eyes of the guide.

Referring further to the drawings, the numeral 1 indicates my device in its entirety, which is preferably made of porcelain or other vitreous material, and is provided with a peripheral groove 2, and has two eyes 3 on diametrically opposite sides of the centre, the two sides of the device at the open ends of said eyes being concaved, 50 with the two eyes somewhat flared at their open ends to cause the same to merge grace-

fully into said concaved faces 4 of the guide.

In Fig. 3 of the drawings I have shown my improved guide held in an ordinary holder 5 formed of spring steel with curved 60 bifurcated ends 6 sprung into the annular groove 2. The holder has an opening 7 at its lower end for securing the same by means of a screw to a braiding or a knitting machine. 65

Instead of the holder here illustrated, my guide may be inserted in the head of an eye-bolt if desired.

My guide cannot be accidentally removed from the holder, nor can it be shaken therefrom by the vibration of the machine. 70

Attention is also called to the fact that with my improved guide the eyes come on opposite sides of the centre of the holder, and are equidistant from said centre, and are spaced apart a distance approximately the same as the distance apart that the threads tend to travel; the result of which is that the threads or strands *a—a* and *b—b* of silk or cotton or other fibre, pass easily 80 and directly through the eyes without lateral strain upon them.

Having described my invention, what I claim as new and desire to protect by Letters Patent is:—

1. In a device of the character described, a guide comprising a body concaved on opposite sides thereof with an intermediate surface connecting said sides at their margins, said device having two eyes extending transversely therethrough on diametrically opposite sides of the centre and in a horizontal plane, said eyes being flared at their open ends and merged into said concave faces, said intermediate surface being provided 90 with means for removable engagement with a holder for the guide.

2. In a device of the character described, a guide comprising a double concave body provided on its edge with means for engagement with a yielding guide holder. 100

3. In a device of the character described, a guide comprising a body having a groove extending around the same for engagement with a guide holder; and a plurality of 105 eyes extending transversely through said body for the simultaneous passage therethrough of a plurality of threads.

4. In a device of the character described, a guide comprising a circular body having 110

a plurality of eyes for the simultaneous passage therethrough of a plurality of threads; and a peripheral groove for engagement with a yielding guide holder.

5. In devices of the character described, a guide comprising a circular body having its periphery provided with a groove for engagement with a holder, and having its faces on opposite sides of its periphery concaved and provided with a plurality of eyes extending through the guide from one face to the other, said eyes being flared at their ends to merge into the concave faces of the guide.

10. In devices of the character described, a guide comprising a circular body having

its periphery provided with a groove for engagement with a holder, and having its faces on opposite sides of its periphery concaved and provided with a plurality of eyes extending through the guide from one face to the other, said eyes being flared at their ends to merge into the concave faces of the guide.

15. In devices of the character described, a guide comprising a circular body having its periphery provided with a groove for engagement with a holder, and having its faces on opposite sides of its periphery concaved and provided with a plurality of eyes extending through the guide from one face to the other, said eyes being flared at their 20 ends to merge into the concave faces of the guide.

In testimony whereof I affix my signature in the presence of two witnesses.

JESSE F. MADDEN.

Witnesses:

EVA ELMOWITZ,
ARTHUR W. PAGE.
